JOHN FLAMMANG, OF ST. LOUIS, MISSOURI, ASSIGNOR TO OTTMAR G. STARK, OF ST. LOUIS, MISSOURI.

PISTON.

1,351,238.

Specification of Letters Patent. Patented Aug. 31, 1920.

Application filed February 25, 1918. Serial No. 219,096.

To all whom it may concern:

Be it known that I, JOHN FLAMMANG, a citizen of the United States, residing at the city of St. Louis and State of Missouri, have 5 invented a new and useful Piston, of which the following is a specification.

This invention relates to pistons.

An object of the invention is to provide a piston which dispenses with the use of 10 piston rings and every other kind of packing and which, because of qualities inherent in its construction, presses closely against the cylinder wall and prevents the passage or escape of the gas, steam or other piston 15 operating agent, and at the same time conforms to all requirements of efficient operation.

Another object is to provide a piston omitting the use of piston rings and packing 20 composed of an expansible portion arranged to fit within a cylinder and press closely against the cylinder wall throughout its circumference, and a head or top plate secured to the expansible portion.

25 A general object of the invention is to provide an improved piston which will function properly and with a high degree of efficiency and which dispenses entirely with the use of all kinds of packing.

30 Various other objects and numerous advantages will appear from the following description, reference being made to the accompanying drawings illustrating the piston in several stages of its construction 35 from the rough casting to the finished piston, and in which—

Figure 1 is a view partly in section illustrating a form of casting from which a piston may be formed in accordance with 40 my invention.

Fig. 2 is a view illustrating the casting after several steps or stages of treatment.

Fig. 3 is a view of the casting after the metal has been placed under tension so as 45 to impart pressure against the cylinder wall when the piston is in the cylinder.

Fig. 4 is an elevation of the casting, the metal above the wrist pin being held under tension ready for the casting to be finished 50 as to its circumferential surface.

Fig. 5 is a view illustrating the casting held under tension within a cylinder, in which the treatment of the body of the piston is finished and made ready for the head 55 plate to be applied thereto.

Fig. 6 is an elevation of the finished piston.

Fig. 7 is a sectional view of the finished piston mounted within a cylinder.

The casting from which the piston body 60 is formed in the particular form illustrated, comprises a lower ring 1, an upper ring 2 and a pair of diametrically opposite connections 3 by which the upper and lower rings are integrally united. 65

An inwardly extending boss 4 is integral with each of the connections 3 and preferably there are two aligned arms 5 extending inwardly from diametrically opposite sides of the upper ring 2 above the bosses 4. As 70 shown, each of the arms 5 is formed with an upward extension 6 at its inner end, said extensions being spaced apart a suitable distance so that when it is desired to compress the upper portion of the cylinder, as herein- 75 after explained, there will be sufficient room for movement of the extensions 6 toward each other.

The casting is then preferably, though not essentially, tapered slightly as illustrated in 80 Fig. 2, and inwardly and downwardly inclined holes 7 are formed through the connections 3 and the bosses 4. The upper ring 2 of the casting is also cut on diametrically opposite sides midway between 85 the connections 3, as indicated at 8. While the cuts 8, as shown, are vertical it will be understood, of course, that they may be inclined or otherwise formed at the option of the manufacturer or user. The relative order 90 of the various steps or stages just described in the manufacture of the piston is unimportant and, of course, I do not restrict myself to unessential details in this particular. 95

After the upper ring has been cut in the desired manner and the inclined holes 7 have been formed, a wrist pin 9 is forced into the holes 7. The wrist pin fits closely within the holes and therefore in order to 100 insert the wrist pin it is necessary to bend or spread apart to a slight extent the connections 3 until the holes 7 are in accurate alignment in which shape the material will be held by the wrist pin. The wrist pin 105 may, if desired, be positively held or locked in its proper position by set screws 10 mounted in the bosses 4.

Next, the two separated parts of the upper ring 2 are forced toward each other in 110

order to bend inwardly and place under tension the connections 3 above the wrist pin. This may be accomplished by passing a bolt 11 through holes in the extensions 6 of the 5 arms 5 and turning the nut on the bolt until the proper result is attained. While the casting is thus retained under tension the periphery of the casting is ground or turned and finished to the diameter of the cylinder for 10 which it is intended, it being understood that the lower ring 1 is of slightly less diameter than the diameter of the cylinder. Thus, when the piston is placed within the cylinder after being finished, pressure will be 15 imparted against the cylinder wall all around, due to the fact that when the open ring 2 was finished it was held under tension to the diameter of the cylinder, and when released from the compressing device 20 the resiliency of the metal will cause the ring 2 to exert the required pressure against the wall of the cylinder.

After the periphery of the piston has been finished while the material is held under tension as described, the piston is placed 25 within a cylinder 12 (Fig. 5) of the same diameter as the diameter of the cylinder for which the piston is intended, thus holding the piston compressed under tension after 30 the bolt 11 is removed. The upper portion of the ring 2 is then cut away below the arms 5, and, in the form shown, an internal groove 13 is formed in the open ring 2. Also, either before the piston is placed in the cylinder or 35 after removal therefrom, as desired, a number of circumferential grooves 14 are formed in the lower ring 1 which grooves are adapted to receive an oil or lubricant whereby the necessary lubricant is applied between the 40 piston and the cylinder in which it operates.

The top or head plate 15 of the piston seats upon the ring 2 and is formed with a cylindrical portion 16 extending into the ring 2. The part 16 is formed with a circumferential flange 17 engaging within the groove 13 45 and thus locking the top or head plate with the body of the piston. It will be understood that the use of the locking flange 17 is optional and that any other appropriate form 50 of device for holding the top plate in connection with the body of the piston may be used.

The spaces between the ends of the separated parts of the ring 2 are closed as to the 55 passage of the gas or other piston operating agent by keys in the form of plates 18 seated in grooves formed in the ends of the ring sections and in the top or head plate of the piston. Thus the plates 18 in addition to preventing the passage of gas between the 60 ends of the ring sections also lock or hold the top plate in connection with the body of the piston, making it unnecessary to employ the retaining flange 17 unless desired. The keys in no way interfere with the freedom of 65 expansion and compression of the piston.

The diameter and circumference of the top or head plate 15 very closely approximate the internal diameter and circumference of the cylinder in which the piston is to operate, so that when the upper ring of the body of 70 the piston is compressed and the piston is placed within the cylinder the diameter of the top or head plate and the diameter of the upper ring of the piston body are very nearly the same. However, before the piston is 75 compressed within the cylinder the upper open ring of the piston body is of larger diameter in the plane of the axis of the wrist pin than the diameter of the top or head plate, the relative arrangement of the parts 80 being clearly understood by reference to Fig. 6.

The upper edge of the ring 1 is beveled to provide a scraping edge 19 which during upward movement of the piston will scrape the 85 oil from the cylinder wall; and the lower edge of the ring 2 is beveled to provide a scraping edge 20 which during downward movement of the piston will scrape the oil from the cylinder wall. 90

From the foregoing it will be understood that my invention is broadly a piston dispensing entirely with the use of piston rings and packing of every kind, and which is so constructed that the necessary pressure is imparted against the cylinder wall to prevent the passage of gas, steam or the like. The resiliency of the metal permits free expansion and contraction of the piston to accommodate itself to any and all variations in the 100 cylinder so that the piston will function properly and with perfect efficiency all the time. 95

I do not restrict myself to any particular mode or manner of constructing the piston 105 in order to utilize the resiliency of the metal to effect the desired results.

I claim:

1. A piston, comprising a split upper ring, a lower ring, connections integrally uniting the upper and lower rings, a piston head detachably supported by the upper ring, and means co-operating with said connections to impart outward pressure to the upper ring to cause it to press against the wall 110 of the cylinder in which the piston is mounted. 115

2. A piston, comprising an upper ring, a lower ring, connections integrally uniting the upper and lower rings and being tensioned to press the upper ring outwardly against the wall of the cylinder in which the piston is mounted, and a piston head plate supported by the upper ring and permitting the upper ring to expand and contract. 120

3. A piston, comprising an upper ring, a lower ring, connections integrally uniting the upper and lower rings and being tensioned to press the upper ring outwardly against the wall of the cylinder in which the piston 130

is mounted, a piston head plate supported by the upper ring and permitting the upper ring to expand and contract, and a wrist pin supported by said connections.

5 4. A piston, comprising an upper ring composed of separate segmental sections, a lower ring, connections integrally uniting the lower ring with the respective segmental sections of the upper ring and being tensioned to press the segmental sections of the upper ring against the wall of the cylinder in which the piston is mounted, and a piston head plate supported by the segmental sections of the upper ring and permitting ex-

10 15 pansion and compression of the upper ring.

5. A piston, comprising an upper ring composed of separate segmental sections, a lower ring, connections integrally uniting the lower ring with the respective segmental sections of the upper ring and being tensioned to press the segmental sections of the upper ring against the wall of the cylinder in which the piston is mounted, a piston head plate supported by the segmental sections of the upper ring and permitting ex-

20 25 pansion and compression of the upper ring, and an oil scraping device in connection with the upper ring for scraping the oil from the wall of the cylinder during downward movement of the piston.

30 35 40 6. A piston, comprising an upper ring composed of separate segmental sections, a lower ring, connections integrally uniting the respective sections of the upper ring with the lower ring, and being tensioned to press said segmental sections against the wall of the cylinder in which the piston is mounted, and a piston head plate removably supported by the segmental sections of the upper ring independently of the lower ring.

45 50 55 7. A piston, comprising an upper ring composed of separate segmental sections, a lower ring, connections integrally uniting the respective sections of the upper ring with the lower ring, and being tensioned to press said segmental sections against the wall of the cylinder in which the piston is mounted, a piston head plate removably supported by the segmental sections of the upper ring independently of the lower ring, and means for holding the piston and head plate in connection with said sections and leaving said sections free for expanding and contracting movements.

60 65 70 8. A piston, comprising an upper ring composed of separate segmental sections, a lower ring, resilient connections integrally uniting the respective sections of the upper ring with the lower ring and arranged to press said sections yieldingly against the wall of the cylinder in which the piston is mounted, and a piston head supported by said sections of the upper ring independently of the lower ring.

65 9. A piston, comprising a ring composed

of separate segmental sections, resilient members integral with said sections for pressing said sections outwardly against the wall of the cylinder in which the piston is mounted, and a head plate in connection with said segmental sections.

nections; a top plate removably connected to the upper ring; and keys holding the top plate in connection with the upper ring.

17. A piston comprising a body composed of a lower ring, an upper ring of larger diameter than the diameter of the cylinder for which the piston is intended, and connections integrally uniting the lower and upper rings; a wrist pin rigid with said connections; a top plate upon the upper ring; and keys holding the top plate in connection with the upper ring and closing the space between the ends of the upper ring.

18. A piston, comprising a piston body having a resilient upper portion capable of expanding to a size in excess of the size of

the cylinder for which the piston is intended and arranged to expand to press against the cylinder wall by the resiliency of the material of said upper portion, a lower portion, 20 connections integrally uniting the upper and lower portions, and a piston head plate supported by the expansible upper portion of the piston body.

19. A piston, comprising a piston body 25 having a resilient upper portion arranged to expand to press against a cylinder wall by the resiliency of the material, and a head plate for the piston supported by said resilient portion.

JOHN FLAMMANG.
